CLAIM

The ornamental design for a briefcase, as shown and described.

DESCRIPTION

FIG. 1 is a front perspective view of a briefcase showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,
FIG. 7 is a bottom view thereof.
The even-length broken lines within the shaded area represent stitching.
